UNITED STATES PATENT OFFICE

135,099

DESIGN FOR A FLASHLIGHT

Henry M. Slocum, New York, N. Y., assignor to Colvin-Slocum Boats, Inc., New York, N. Y., a corporation of New Jersey

Application June 16, 1942, Serial No. 107,221

Term of patent 14 years

To all whom it may concern:

Be it known that I, Henry M. Slocum, a citizen of the United States, residing at New York, county of New York, State of New York, have invented a new original, and ornamental Design for Flashlight, of which the following is a specification, reference being had to the accompanying drawing, forming a part thereof.

from the left of Figure 2, and

from the right of Figure 2.

I claim:

The ornamental design for a flashlight, substantially as shown.

HENRY M. SLOCUM.
